UNITED STATES PATENT OFFICE.

HIRAM D. HARRIS, OF NORCROSS, GEORGIA.

WINDOW SHADE AND CURTAIN SUPPORT.

Application filed April 25, 1922. Serial No. 556,551.

To all whom it may concern:

Be it known that I, HIRAM D. HARRIS, a citizen of the United States, residing at Norcross, in the county of Gwinnett and State of Georgia, have invented a new and useful Window Shade and Curtain Support, of which the following is a specification.

This invention relates to window shade and curtain rod holders.

10 The object of the invention is to provide a simply constructed, neat holder of this character which may be quickly applied without requiring any measurements to determine the exact place to locate a fixture 15 so that a novice may put up curtains and shades by simply screwing up two screws which are carried by the fixture.

Another object is to provide a fixture of this character, the application and removal 20 of which will not appreciably mar the wood work and yet will be reliably secured.

Another object is to provide a fixture of this character which will hold the shade roller so that it cannot slip out of its bracket 25 and unwind.

With the foregoing and other objects in view which will appear as the description proceeds, the invention resides in the combination and arrangement of parts and in 30 the details of construction hereinafter described and claimed, it being understood that within the scope of what is claimed, changes in the precise embodiment of the invention herein disclosed, may be made 35 without departing from the spirit of the invention.

In the accompanying drawings:

Figure 1 represents a front elevation of a fixture constructed in accordance with this 40 invention, shown applied.

Fig. 2 is a detail perspective view of one of the brackets constituting a part of the invention with a portion of the shade roller shown mounted therein, and

45 Fig. 3 is a detail sectional view showing the means for connecting the fixture to a window frame.

In the embodiment illustrated, the device constituting this invention comprises a comparatively narrow bar 1 preferably composed of wood of a length substantially corresponding to the width of the curtain to be carried thereby and the window in connection with which it is to be used.

55 Mounted at opposite ends of this bar on its outer face are two brackets 5 and 10

which are exactly alike in construction except that one is made right and the other left, and one has a rectangular shade roller bearing such as is usual in attachments of 60 this kind, and the other a circular aperture to receive the round pintle of the shade roller.

The bracket 5 which supports the left hand end of the shade roller R is made L-shaped in form with the base plate 6 thereof equipped at its corners with screw receiving apertures 7 to provide for its detachable connection with the bar 1. The outwardly extending arm 8 of the bracket has a rectangular opening 9 therein for the reception of the angular pintle P of the roller R as is shown clearly in Fig. 2.

The arm or plate 6 of bracket 5 is provided with longitudinally spaced laterally extending curtain rod supporting hooks 11 and 12 which are designed to receive the ends of rods 3 and 4 arranged one in advance of the other for supporting draperies of different kinds.

In the use of this fixture, the brackets 5 and 10 are first mounted on the bar 1 and adjusted in proper position to receive the shade roller R and the curtain rods 3 and 4. The shade S may then be mounted in the 55 brackets and the rods carrying the draperies engaged with the hooks 11 and 12 or the draperies may be applied if desired after the fixture has been hung. To mount the shade roller, the angular pintle P is first 90 inserted through the aperture 9 in the bracket arm 8 and then the other bracket is engaged with the round pintle at the end of the shade roller, and said bracket secured to the bar 1. When so mounted, it 95 will be impossible for the shade roller to become accidentally disengaged from its bracket and thus avoid unwinding of the spring of the roller which frequently occurs with the brackets ordinarily employed 100 for this purpose.

The bar 1 is equipped with a pair of screws as 2 which extend through the plates 6 of the brackets and are designed to be engaged with the window frame F so that in 105 applying the fixture, all that is necessary is to position the bar 1 at the point where it is desired to hang the shade and curtains, and then screw home the screws 2 and the fixture will be already for use without requiring any measurements or adjustments.

The use of this fixture eliminates all

worry and labor in putting up window shades and curtains and also avoids any appreciable marring of the wood work, since the only apertures made therein are the holes 5 which receive the screws 2.

When the draperies are hung, the bar 1 will be practically concealed or if desired, it may be decorated to conform to the window frame in connection with which it is to be 10 used so that the mounting thereof on said frame will not be noticeable in case the draperies do not conceal it.

I claim:

A device of the class described comprising a bar of a length corresponding substantially to the width of the window in connection with which it is to be used, two 15 longitudinally spaced L-shaped brackets mounted on said bar, one arm of each

bracket constituting a substantially rectangular attaching plate and the other apertured to receive a roller pintle, said attaching plate being of a width corresponding to that of said bar and overlying the bar, said plate having apertures at its corners to receive 25 screws for connecting it to the bar, and up-turned longitudinally spaced alined hooks carried by said plate, said plate and bar having registering screw receiving apertures to connect the bar to a window frame. 30

In testimony that I claim the foregoing as my own, I have hereto affixed my signature in the presence of two witnesses.

HIRAM D. HARRIS.
